UNITED STATES PATENT OFFICE.

WILLIAM H. MILLIKEN, OF SAN FRANCISCO, CALIFORNIA, ASSIGNOR OF
ONE-HALF TO FREDERICK N. WOOD, OF SAME PLACE.

HYDRAULIC ELEVATOR.

SPECIFICATION forming part of Letters Patent No. 243,391, dated June 28, 1881.

Application filed August 13, 1880. (No model.)

To all whom it may concern:

Be it known that I, WILLIAM H. MILLIKEN, of the city and county of San Francisco, State of California, have invented a new and useful 5 Improvement in Hydraulic Elevators, of which the following is a specification.

My invention relates to that class of hydraulic elevators which have a plunger fastened to and extending down from underneath 10 the floor or bottom of the cage or platform carrying the load into a cylinder setting vertically and placed below the lowest point that the cage or platform retires to when operating, the erection of such devices generally necessitating 15 the sinking of the said cylinder within a well below the basement-floor of the building in which they may be applied; and my said invention consists in certain improvements in the water-cylinder, and its adaptation to the 20 purpose of forming a lining for the well, and to be in itself the tube used in boring or sinking the well.

Referring to the accompanying drawings, forming a part of this specification, Figure 1 represents a sectional elevation of my improved cylinder and plunger in two broken lengths, and sealing-plug. Fig. 2 is a plan of sealing-plug. Fig. 3 is a plan of piston. Fig. 4 shows a sectional view of my improved manner of 25 connecting the plunger-head to under side of platform or cage, to accommodate any canting of the cage which may occur.

Like letters of reference refer to like parts in all the figures of the drawings. 30 To make my invention clearly understood I will state that heretofore in elevators of the class named the working-cylinder has generally been placed in a well already formed, either in the hard rock, requiring no lining or 35 in a brick-lined well, or in a well lined with the ordinary Artesian-well tubing used in sinking the well. Now, with my improvement I propose to avoid the expense of making any lining for the well other than is formed by my 40 working-cylinder itself, which may be made of the ordinary deep-well tubing used by Artesian-well borers.

In the drawings, A is the working-cylinder, formed of the wrought-iron tubing named. It 45 should be of the best quality and sufficiently thick to admit of the joint at a being of proper

strength, for since the joint must not project inside or out beyond the remainder of the tube, if the tube be too thin this joint would be defective. This working-cylinder may consist of 55 many lengths, according to the depth of the well, and is open at the bottom during the process of sinking it.

B is a plug of cast-iron, formed of two disks, b b', capable of being drawn together by the 60 central bolt, b'', in such a manner as to squeeze out a packing, C, against the sides of the tube, which packing is inserted previous to the plug being placed in position. The bolt b'' will be screwed up or loosened with a socket-wrench 65 attached to any suitable tools of the well-borer. The top of this working-cylinder, after it is sunk into its final resting-place, is mounted with a suitable stuffing-box, D, having a gland, E, the said stuffing-box being screwed onto the 70 end of the working-cylinder, or in any other suitable way secured tightly thereon.

The ingress and egress opening F for the water is formed just below the stuffing-box on the same casting, a pipe being screwed into 75 the opening, upon which pipe the usual supply and exhaust cock is attached.

G is the plunger, a stout metallic tube, preferably of wrought-iron, smooth on the outside as far as it passes through the stuffing-box, 80 and terminating on the bottom with what I call a "cataract" piston, H, which piston is screwed onto the end in the manner shown in Fig. 1. This plunger G may be in as many 85 pieces as convenient, the joints being made by means of the internal coupling, I, so as to leave the outside of the plunger perfectly smooth.

My cataract-piston H is simply a cap screwed onto the lower end of the plunger, having an 90 exterior diameter equal to the interior diameter of the working-cylinder, so that it may form a guide to maintain the true perpendicular position of the plunger; but this piston does not completely obstruct the passage of the water, 95 for it has grooves J cut upon its periphery, taking by the combined areas of their cross-section an area equal to about one-half of the total area of the inlet-opening F, so that when the water is admitted to the cylinder it may 100 find a passage-way to the under side of the piston, so as to give a pressure thereupon to

raise the plunger and its superimposed load, and also to permit the egress of the water from underneath the piston when the exhaust-cock is opened for the purpose of allowing the 5 plunger to fall, the fall being obtained with a gentle motion, not capable of being accelerated beyond the limit allowed by the area of the 10 passage the grooves in the piston provide, thus making a most complete automatic safety 15 device which, not having any liability to get out of order, would be especially desirable in elevators carrying passengers. These grooves J may be found to be too large or too small after the elevator has run an extended period, 20 either on account of their becoming choked by corrosion or impurities in the water, or by reason of the piston having become worn; but whatever occurs to change their condition must necessarily be so gradual and slow of progress 25 that ample opportunity will be given to apply the remedy which will naturally be suggested.

The cap of the plunger K, which is secured just below the floor of the cage, (the cage not being shown in the drawings,) may be simply 25 a flat round disk screwed onto the plunger, as in Fig. 1, and fastened to the cage by screw-bolts, or it may be a ball-and-socket joint, as in Fig. 4, which latter construction will permit the canting of the cage without causing 30 any side strain upon the plunger, which might, in some cases, be disadvantageous, as tending to increase friction and otherwise interfere with the smooth action of the machine. This arrangement shown in Fig. 4 may be thus described:

35 L is a collar with convex faces, top and bottom, screwed on end of plunger. M is a wrought-iron plate fastened under the timbers of the cage, made concave to fit the collar L; 40 and N is an annular plate, also concave, as shown, to fit under side of collar, and when bolted to the plate M confines the collar and secures the cage to the plunger, as clearly shown in the figure.

If preferred, and found suitable, the sealing- 45 plug B may be dispensed with and a simple seal of hydraulic cement poured into the cylinder when set in its final position.

The operation of the supply and exhaust cock is not materially different from what is 50 now practiced, and I need not enter into any description with reference to it.

The plunger G, being made of wrought-iron tube in the manner described, may be so light and yet sufficiently strong that the cumbersome and dangerous counter-balance usually applied in this class of elevators may be dispensed with; and although a slightly increased quantity of water will necessarily be expended 55 in operating, in consequence of the imperfect balance resulting, still it is thought that so many advantages as to safety and convenience arise from the counter-balance being dispensed with that it will be found desirable to submit to the additional expense of the water, rather 60 than incur the inconvenience and risk when the counter-balance is employed.

What I claim as my invention, and desire to secure by Letters Patent, is as follows:

1. In a hydraulic elevator, the combination 70 of the open-bottom well-lining A, through which the well is bored, plug B, placed after well is bored, and stuffing-box D, having gland E, the whole forming a working-cylinder, substantially as and for the purpose herein described.

2. In a hydraulic elevator, the adjustable joint connecting the head of the plunger G with the cage, consisting of the collar L and plates M and N fastened together, as a means 80 of accommodating the canting of the cage, as and for the purpose herein described.

WILLIAM H. MILLIKEN.
